ADHESIVE APPLYING MACHINE

Wilbur L. MacKenzie, Beverly, Mass., assignor to
 United Shoe Machinery Corporation, Flemington, N. J., a corporation of New Jersey

Application February 11, 1942, Serial No. 430,345

13 Claims. (Cl. 91—50)

This invention relates to a machine for applying a coating to a shoe part and is directed more particularly to the application of adhesive to the lasting margin of the upper of rubber shoes of the type commonly known as tennis shoes or sneakers.

In the manufacture of rubber shoes of this type, the upper is assembled preparatory to lasting by stitching the tongue, which includes the tip, to the forepart of the quarters and the junior to the back part of the quarters, thereby providing what is called a circular or closed upper. The lower edge of the combined tongue and tip where it is joined to the forepart of the quarters does not coincide with the lower edge of the quarters, as illustrated. This is also true of the lower edge of the junior. As a result, the lasting margin of the inner surface of the upper to which the adhesive is to be applied so that the upper may be pulled in over the insole and caused to adhere thereto prior to attachment of the outsole is not of uniform thickness. In order, therefore, to insure the application of adhesive to the entire lasting margin, the lasting margin heretofore has been held against an adhesive applying roll by a plurality of spring fingers, each finger acting independently of the adjacent finger. It is quite common in the manufacture of tennis shoes and sneakers to decorate the uppers by stitching thereto wide strips of rubber. These strips are carried down to the lower edge or lasting margin of the upper so that they are lasted in with the upper. Accordingly, when adhesive is applied to the lasting margin, the rubber strips will come in contact with the aforesaid spring fingers. The rubber has a high coefficient of friction and therefore resists movement between the spring fingers and the adhesive applying roll. If the operator attempts to force the work at this point, the rubber strips bunch up and prevent the work from being moved further without either damaging the work or stalling the machine.

It is an object of the invention to provide improved means to facilitate passage of the work through the machine to eliminate the aforesaid bunching caused by the excessive friction produced between the rubber strips and the spring fingers.

This is accomplished, as a feature of the invention, by vibrating the spring fingers, which hold the work against the applying roll, during the movement of the work between them and the applying roll, the vibration of the fingers being confined to movement toward and away from the surface of the applying roll such that any one point on the fingers moves always in a single vertical plane.

The character of the work depends upon the type of material used for the manufacture of the

shoes, that is, a very light fabric or a very heavy fabric may be employed. The spring fingers may, in one case, be sufficiently stiff to hold the different thicknesses of the lasting margin close against the applying roll, but when a heavier or lighter material is used, these fingers may be either not stiff enough or too stiff. Accordingly, another feature of the invention resides in means co-operable with the spring fingers constructed and arranged to vary the unsupported length of the fingers so as to vary their stiffness for different weights of work.

The machine will now be described in detail with reference to the accompanying drawings, in which

Fig. 1 is a side elevation of substantially the entire machine;

Fig. 2 is a view in elevation and on a larger scale of the applying roll and the work supporting fingers;

Fig. 3 is an end elevation of the parts shown in Fig. 1 as seen from the left side;

Fig. 4 is an end elevation, partly in section, of the supporting fingers and the support therefor;

Fig. 5 is a fragmentary view in elevation of the applying roll with the spring fingers in section, showing the way the spring fingers hold the lasting margin of the work against the applying roll; and

Fig. 6 shows an angular view of a rubber shoe top or upper, wrong side out, showing the overlap of the junior, tongue and vamp along the lasting margin.

The machine as disclosed herein comprises, in general, a base 10 from which there rises a pedestal-like frame 12, the frame 12 supporting the operating parts of the machine which consist of an adhesive applying roll 14 and means 16 for holding the work against the applying roll.

The applying roll 14 is mounted to rotate with a shaft 18 which is journaled in the frame of the machine and driven by gearing (not shown). The surface of the applying roll 14 is supplied with adhesive in the customary manner by a series of transfer rolls, one of which is shown at 20.

The work to which the adhesive is to be applied is what is called a closed or circular upper 50 and, as shown in Fig. 6, comprises quarters Q joined at their forepart by a tongue T, which includes the tip. The points at which the edges of the tip are stitched to the quarters do not coincide exactly with the lower edge of the quarters, as illustrated. This is also true of the lower edge of the junior which is short of the lower edges of the quarters to the rear part of which it is stitched. Accordingly, the lasting margin to which the adhesive is to be applied is not of uniform thickness and, in order to hold

this uneven margin against the applying roll 14 to insure the application of adhesive to every part thereof, the holding means is made up of a plurality of spring fingers 22 (Figs. 2 and 5) which are arranged side by side below the surface of the applying roll and which may yield within limits according to the thickness of the work at any point. One end of each of these fingers 22 is secured by a bar 24 to a segment 26 formed on a U-shaped bracket 28, the bracket being fastened to one arm 38 (Fig. 1) of a bell crank 32 which is pivotally supported on the frame of the machine at 34. It is to be observed that by this arrangement the fingers may be moved to and from the surface of the applying roll, but that they do not have any lateral movement in the direction of the movement of the work as it is drawn between the fingers and the roll. The opposite arm 36 of the bell crank is connected by a link 39 to a treadle rod 40 by which the arm 30 may be raised to bring the spring fingers into a position co-operating with the applying roll 14. The upper end of the rod 40 is guided by a link 41 fastened at one end to the rod 40 and at its opposite end to the frame. A lug 35 formed at the pivoted end of the link 38 co-operates with a flat 37 formed on the end of the arm 36 to prevent rotation of the link 38 beyond a position at right angles to the arm when the treadle is depressed for reasons which will appear hereinafter. An adjustable stop 42 is provided on the frame of the machine which co-operates with a boss 43 formed on the arm 30 and supports the arm 30, when the treadle is released, in its inoperative position.

As heretofore explained, the decorative rubber strips which are stitched to the upper create so much friction when they move between the applying roll and the spring fingers that the rubber strips bunch and prevent proper feeding of the work. Accordingly, novel supporting mechanism is provided, permitting the rubber strips to move between the applying roll and the supporting fingers without causing bunching. This mechanism rapidly vibrates the support for the spring fingers to and from the applying roll. The rapid vibration of the support for the spring fingers momentarily lessens the grip between the applying roll and the spring fingers, thereby permitting the work to move forward a small distance, and then holds the work against the applying roll so that the adhesive will be brought into intimate contact therewith. Thus, by intermittently pressing the work against the applying roll and relieving the pressure, the operator is able to draw the work between the applying roll and the supporting fingers quite uniformly without causing bunching of the rubber strips. To accomplish this, the link 38 which is connected to the lower end of the arm 36 of the bell crank 32 is joined by an adjustable rod 46 to one end of a lever 44 pivoted at 47 on the frame of the machine. The opposite end of the lever 44 is provided with a cam roll 48 which rides in a cam groove 50 formed in the peripheral surface of a cam 52 mounted on a shaft 53 which is driven by a pulley 55 and constitutes the drive shaft for the applying roll and the transfer rolls which are connected thereto by suitable gearing not shown herein. The link 38 and rod 46 form a toggle joint connection between the arm 36 and the lever 44. Consequently, when the work supporting means 16 is in its inoperative position resting against the stop 42, the oscillation of the lever 44 will not produce vibration of the bell crank 32. This is

clear from an inspection of Fig. 1, which shows that until the treadle 40 is moved down to bring the work supporting means 16 into a co-operating position with respect to the applying roll, the toggle is bent and the link 38 will merely oscillate on the lower end of the arm 36. When, however, the treadle rod 40 is lowered, the link 38 will, by rotation about its pivot, be brought into alignment with the adjustable rod 46 and thereby produce vibration of the bell crank 32. The lug 35 prevents further rotation of the link 38 by contact with the flat 37. The range of the vibration may be adjusted by rotation of a turnbuckle 45 which permits lengthening or shortening of the rod 46.

Fabrics used for manufacturing rubber shoes vary considerably in stiffness and for this reason it is desirable to be able to vary the stiffness of the supporting spring fingers 22 thereby to permit variation of the supporting pressure. Accordingly, a bar 54 (Fig. 4) is mounted at the inner side of the spring fingers 22 with one longitudinal edge thereof in contact with the undersides of the spring fingers, the contacting edge of the bar being rounded off to provide substantially fine contact between the bar and the fingers. The bar is rotatably supported by a spindle 56 journaled in the walls of the U-shaped bracket 28, the axis of the spindle lying substantially along the locus of the centers of the fingers. By turning the bar 54 about the spindle 56, the unsupported length of the spring fingers may be varied, thereby varying the stiffness of the fingers. The position of the bar 54 may be fixed at any particular point by a setscrew 58 which is passed through the segment 26 and sets up against the inner edge of the bar.

It is difficult to procure spring steel which is of such uniform quality that, when made up into 40 spring fingers of the type employed herein in which only one end of each finger is fastened, the free ends of the fingers will all lie in the same plane. In order to keep the fingers in the same plane so that no one of them will approach 45 too close to the applying roll and thereby pick up adhesive which ultimately would soil the display side of the upper, a rod 60 is mounted on the bracket 28 in a position to overlie the upper free ends of the fingers, as shown in Figs. 3 and 4. This prevents the fingers from moving beyond 50 a predetermined position with respect to the applying roll but at the same time permits the fingers to yield inwardly to accommodate variations in the thickness of the work.

A gage 62 for guiding the inner edge of the work as it is moved through the machine is adjustably fastened to the arm 30 which supports the fingers 22. This gage is adjustable so that the width of the band of adhesive may be varied in accordance with the kind of work being handled.

When the machine is in use, the operator takes an upper and turns it wrong side out, as shown in Fig. 6. The work is then rested upon the 65 spring fingers 22 with its edge against the gage 62. The operator then raises the spring fingers by depressing the treadle rod 40, thereby bringing the work into contact with the applying roll and at the same time moving the link 38 into alignment with the rod 46 to cause the reciprocation of the arm 44 to vibrate the bell crank 32. The operator feeds the work through the machine by hand and the rapid vibration of the work support 16 is sufficient to hold the work in 70 intimate contact with the applying roll and yet 75

to permit the rubber strips which are attached to the outer surface of the upper to pass between the applying roll and the work holding means 16 without bunching.

Having described my invention, what I claim as new and desire to secure by Letters Patent of the United States is:

1. In a machine for applying adhesive to a shoe part, an adhesive applying roll, resilient means for holding the work against the adhesive applying roll, said resilient means being fixed from lateral movement in the direction of movement of the work but movable to and from the surface of the applying roll, and means for vibrating said resilient means with respect to the surface of said adhesive applying roll.

2. In a machine for applying adhesive to a shoe part, applying means having an applying surface, a plurality of yieldable fingers for holding the work against the surface of the applying means as it is passed therebetween, said fingers and roll being superposed and said yieldable fingers being fixed from lateral movement with the work but movable to and from the surface of the applying means, and means for vibrating said fingers as a whole with respect to the surface of the applying means irrespective of the planar position of any individual finger at any given time.

3. In a machine for applying adhesive to a shoe part, applying means, yieldable work holding means for holding the work against the applying means, means co-operable with said yieldable work holding means constructed and arranged to vary the yieldability of said work holding means, and means for vibrating said work holding means to and from the applying means.

4. In a machine for applying adhesive to a shoe part, applying means, a plurality of yieldable fingers for holding the work against the applying means, means co-operable with said fingers to vary their yieldability as a whole, and means for vibrating said fingers to and from the applying means.

5. In a machine for applying adhesive to a shoe part, applying means, a plurality of yieldable fingers supported at one end adjacent to the applying means with their free ends extending in an arc close to the surface of the applying means, means co-operable with said fingers to vary their unsupported lengths as a unit, and means for vibrating said fingers to and from the applying means.

6. In a machine for applying adhesive to a shoe part, an applying roll, an arm adjacent to the applying roll, a plurality of yieldable fingers fixed at one end to said arm, the free ends of said fingers extending into co-operating positions with respect to the applying roll, a bar mounted on said arm with a portion thereof in contact with the inside of the fingers, said bar being movable to change its position of contact with the fingers, and means for vibrating said arm.

7. In a machine for applying adhesive to a shoe part, an applying roll, an arm adjacent thereto, a plurality of yieldable fingers for holding the work against the applying roll, said fingers being fixed at one end to said arm with their free ends extending close to the surface of the applying roll, means for restraining the movement of the fingers out of a common plane away from the arm but permitting unrestrained movement toward the arm, and means for vibrating

said fingers as a whole with respect to the applying roll.

8. In a machine for applying adhesive to a shoe part, an applying roll, an arm adjacent thereto, a plurality of yieldable fingers for holding the work against the applying roll, said fingers being fixed at one end to said arm with their free ends extending close to the surface of the applying roll, a rod in contact with the outer surface of the free ends of the fingers, said rod serving to restrain movement of the fingers away from the arm and permitting movement inwardly thereof, and means for vibrating said arm.

9. In a machine for applying adhesive to a shoe part, applying means, a plurality of yieldable fingers supported at one end adjacent to the applying means with their free ends extending in an arc close to the surface of the applying means, means engaging the top sides of the free ends of the fingers, and means engaging the undersides of said fingers, said last-named means being adjustable relative to the fingers from their supported to their unsupported ends.

10. In a machine for applying adhesive to a shoe part, an adhesive applying roll, a plurality of spring fingers for holding the work against the adhesive applying roll, means for supporting the spring fingers adjacent to the adhesive applying roll, said means being fixed from lateral movement in the direction of movement of the work but movable to and from the surface thereof, oscillatable means, and adjustable means connecting said supporting means to the oscillatable means to produce vibration thereof to and from the surface of the applying roll.

11. In a machine for applying adhesive to a shoe part, an adhesive applying roll, a plurality of spring fingers for holding the work against the adhesive applying roll, a support for the spring fingers, said support being fixed from lateral movement in the direction of movement of the work but movable to and from the surface of the applying roll, a lever, cam means for oscillating said lever, toggle means connecting said lever to the support, and means operable to straighten said toggle means to produce vibration of the lever to and from the surface of the applying roll.

12. In a machine for applying adhesive to a shoe part, an adhesive applying roll, a plurality of spring fingers for holding the work against the adhesive applying roll, a support for the spring fingers operable to move the spring fingers from inoperative to operative position, oscillatable means, means forming a connection between the support and said oscillatable means, and means for causing said connection to transmit the oscillations of said oscillatable means to said support when the support is in operative position to produce vibration thereof.

13. In a machine for applying adhesive to a shoe part, an adhesive applying roll, a plurality of spring fingers for holding the work against the adhesive applying roll, a support for the spring fingers operable to move the spring fingers from inoperative to operative position, oscillatable means, means forming a connection between the support and the oscillatable means, and means for moving the support from inoperative to operative position, said means simultaneously causing said connection to transmit the oscillations of said oscillatable means to said support.
